UNITED STATES PATENT OFFICE.

SYDNEY W. WILLIAMSON AND EDWARD DISHER, OF CINCINNATI, OHIO.

DESIGN FOR A DESK.

Application filed July 6, 1921. Serial No. 482,852. Term of patent 3½ years.

To all whom it may concern:

Be it known that we, SYDNEY W. WILLIAMSON and EDWARD DISHER, both citizens of the United States, residing at Cincinnati, in the county of Hamilton and State of Ohio, have invented a new, original, and ornamental Design for Desks, of which the following is a specification, reference being had to the accompanying drawings, forming a part thereof.

In the drawings:

The figure illustrates in perspective our new, ornamental design for desks, the view illustrating the desk closed.

We claim:

The ornamental design for a desk, as shown.

SYDNEY W. WILLIAMSON.
EDWARD DISHER.
